HINGED CONTAINER

Filed April 11, 1946

UNITED STATES PATENT OFFICE

2,555,473

HINGED CONTAINER

Charles U. Deaton, Centralia, Ill., assignor to
McStay Jackson Co., Chicago, Ill., a copart-
nership

Application April 11, 1946, Serial No. 661,301

6 Claims. (Cl. 220—31)

1

My invention is concerned with improvements in a hinge structure which is particularly adapted for use on a container such as a ladies' compact.

An object of my invention is to provide a separable hinge structure which is particularly adapted to be incorporated in a container and the closure member therefor, along any desired number of the sides thereof, whereby the closure member may be moved with respect to the container, by hinging movement about any one of the sides along which the hinge structure has been provided, the hinge structure along the remaining sides separating upon movement of the closure member.

Another object of my invention is to provide a container or compact comprising complementary sections having a plurality of abutting edges connected by separable hinges whereby one section may be hinged with respect to the other section along any desired one of said abutting edges.

Another object of my invention is to provide in a container having a body portion, a top portion, and a plurality of substantially straight sides, separable hinge structures separably connecting the top portion to the body portion along said sides, whereby the top portion may be hinged with respect to the body portion along any of said sides.

A further object of my invention is to provide an improved separable hinge construction for hingedly connecting one movable member to another movable member.

Other objects and advantages will be apparent from the preferred form of my device which is shown, by way of illustration, in the accompanying drawings wherein:

Fig. 1 is a plan view of a ladies' compact which has incorporated therein my improved hinge structure along all four sides of the compact;

Fig. 2 is a section on the line 2—2 of Fig. 1;

Fig. 3 is a side view, to an enlarged scale, of my compact with the members in closed position;

Fig. 4 is a side view similar to Fig. 3 with the members in partly opened position;

Fig. 5 is a view on the line 5—5 of Fig. 4;

Fig. 6 is a view on the line 6—6 of Fig. 4;

Fig. 7 is a view on the line 7—7 of Fig. 4; and

Fig. 8 is an enlarged section through a portion of the hinge structure with the compact members in partially hinged position.

The preferred form of my invention is illustrated in the drawings as embodied in a ladies' compact comprising two shallow shell-like complementary sections 10 and 11. One section 10,

which, for convenience, may be referred to as the bottom section, is provided with an inner circular recessed portion 12 for the reception of make-up material, such as powder or rouge. A gasket 13 surrounds the recess 12 and a retaining screen 14 is secured over the same for retaining the material therein. The other section 11, which may be referred to as the top section, is provided with an inner circular recess 15 adapted to receive therein a mirror 16 which may be permanently secured therein in any desired manner as by an inwardly directed shoulder or bead 17.

The two sections 10 and 11 are provided along each side with a separable hinge construction 18 so arranged that the compact may be opened by hinging or pivoting the top about any desired one of the four sides of the compact, each said hinge construction being provided with means for releasably retaining the separable portions of the hinge construction 18 in connected or interengaged relation when the two sections 10 and 11 are in closed relation, and each said hinge retaining means being releasable when it is desired to open the sections about any one of the other hinged sides of the compact.

The separable hinge structure 18 comprises complementary cooperating members preferably formed integral with the top and bottom container sections 10 and 11 along adjacent sides of the same. The hinge or pivot line which is in the plane of the inner surface of each container section is indicated at 19 (Figs. 1, 4, 5). A series of circular ears 20 are arranged in spaced relation along the edge of the section with the hinge line 19 approximately through the centers of the same. In the form illustrated the ears 20 gradually decrease in size from the center to the outer end of the hinge structure to conform to the curved shape of the container. The portions of the ears 20 which extend above the inner face of the section 10 have inwardly and upwardly sloping surfaces 21 and 22, for a purpose to be described. An end ear 23 merges into the body of the section and is provided on its inner face with an inwardly directed projecting member 24 which functions as a hinge pintle when the structure operates as a hinge cooperating with a hinge socket 25 in the ear 26 on the top section 11, the socket 25 being provided with a downwardly directed slot 27 to permit passage of the member 24 into the socket. On the other end of the hinge structure the ear 28 is provided with a recess or socket 29 having an upwardly directed slot 30 which permits passage into the socket of a co-

operating hinge pintle 31 extending inwardly on the ear 32 on the top section 11.

The hinge pintle 31 and supporting ear 32 on the top section 11 are the same structure as hinge pintle 24 and supporting ear 23 on the bottom section 10 while the ear 26 and its socket 25 on the top section 11 are the same structure as the ear 28 and its socket 29 on the bottom section 10. Referring to Figs. 6, 7 and 8, the pintle member 24 is provided with vertical side surfaces 33, 34 which slope slightly inwardly and upwardly from the center toward the top similar to surfaces 21, 22 on the ears 20 and curved top and bottom surfaces 35, 36. The slot 27 in the socket carrying ear 26 is slightly wider than the width of the pintle 24 and will permit passage of pintle 24 into position in the socket 25 only when the pintle is moved in substantial vertical alignment with the socket. After the pintle 24 has fully seated in the socket 25 relative rotation of the ears 23 and 26 will lock the pintle 24 in the socket 25, the top and bottom surfaces 35, 36 of the pintle engaging the walls of the socket 25. The section shown in Fig. 8 illustrates the position of the pintle 24 in the socket 25 after the sections 10 and 11 have been opened a short distance. I have illustrated the hinge pintle 24 extending only partially between the ear 23 and the adjacent ear 20 on the bottom section with the cooperating socket 25 and slot 27 extending a slightly greater distance in the ear 26. It may be desirable to have the pintle and its cooperating socket a different length, as for example, the entire length of the space between ears 23 and 20. The socket must be sufficiently long to accommodate the pintle and provided with a slot of sufficient length to permit the pintle to pass into position for rotation in the socket. It will be understood that any number of cooperating pintles and sockets may be embodied in the hinge construction. As illustrated in use on my compact the parts of the hinge on each compact section are, per se, identical in structure. They are arranged complementary to each other when the compact sections are in proper relation for interengagement and use.

A series of circular ears 37 provided on the top section 11 have downwardly and inwardly sloping side surfaces 38 and 39 and are arranged to interengage between the ears on the bottom section 10 when they are moved toward each other from the disengaged open position shown in Fig. 4 to closed interengaging position. The ears 37 are the same structure as ears 20 and the sloping side surfaces 21, 22 and 38, 39 provide clearance for the movement of the ears into interengaged relation when they approach each other at an angle, as illustrated in Fig. 4.

In order to prevent the separable hinge structure from becoming disengaged when the container sections are in normal closed position, an ear 40 on the top section 11 is provided with a laterally projecting nib or protuberance 41 and an ear 42 on the bottom section 10 is provided with a cooperating laterally projecting nib or protuberance 43, the projecting portions of the nibs being constructed to snap past each other when the ears 40 and 42 are moved into interengaged juxtaposed position (Fig. 3). When the structure functions as a hinge the nibs 41 and 43 move with their respective ears in opposite directions away from each other and do not interfere with the hinging movement until the container sections have been moved to open position which as indicated in dotted lines in Fig. 4 is a little

more than a right angular relationship when the nib on each section engages with the outer surface of the other section and prevents further hinging movement. When it is desired to separate the hinge members along one side of the container in order to pivot or swing the sections about another side of the container, the nibs 41, 43 may be readily snapped past each other by pressure applied with the fingers. Stop members 44 and 45 aligned with the fastener nibs 41, 43 are provided on the respective container sections 11 and 10 to provide additional stop members and to avoid undue strain on the nibs 41, 43 when the latter function as stop members with the container sections in open position.

While I have illustrated my improved hinge construction applied to a compact or similar container, I contemplate using it in any arrangement where it is desired to separably hinge one member to another. As applied to my compact it permits the user to hinge the sections of the compact about any one of its sides or edges. In any other arrangement its use will facilitate hinging one member with respect to another about one side or about any one of a plurality of abutting sides or edges whenever it is desired to do so.

I claim:

1. A separable hinge construction for separably connecting two members which comprises complementary interengaging ears spaced along the hinge line on each member, a hinge pin centered on the hinge line and extending between a pair of spaced ears on one member, a cooperating ear on the other member having a hinge socket therein and engageable over the hinge pin, interengaging protuberances on adjacent cooperating ears whereby when the ears are in interengaging relation the two members may be pivoted about the hinge line and the structure will function as a hinge or the members may be separated by snapping the protuberances past each other and moving the separable hinge members apart.

2. A container comprising relatively shallow complementary container sections generally rectangular in shape, a separable hinge construction along each side of the container, said hinge construction comprising complementary interengaging members integral with each container section, and releasable snap-acting interengaging projections on said members whereby the hinge members will be releasably held in interengaging relation when the container sections are closed and whereby the container sections may be hinged along any one of the container sides upon releasing the hinge constructions along all the other sides.

3. A container as claimed in claim 2 wherein the hinge members comprise flat sided pins and cooperating socket bearing members having restricted side openings adapted to separably receive the pins when in aligned relation and retain the same in interlocked rotatable relation when they are thereafter relatively rotated.

4. A separable hinge construction for connecting two members which comprises complementary interengaging ears spaced along a hinge line on each member, a hinge pin centered on the hinge line and extending along said line in the space between a pair of ears on one member, a cooperating ear on the other member having a hinge socket formed therein and engageable over the hinge pin, interengaging latching formations on adjacent cooperating ears whereby when the ears are in interengaging relation the two mem-

bers may be pivoted about the hinge line and the structure will function as a hinge or the members may be separated by disengaging the latching formations and moving the separable hinge members apart.

5. A separable hinge construction as recited in claim 1 and stop members on said ears limiting the opening movement of said hinge member.

6. A separable hinge construction as recited in claim 4 wherein said hinge pin is provided with flat sides and wherein the ear having the socket for receiving the same is provided with a restricted side opening to permit the pin to be received therein when in aligned relation and to thereafter retain the same in rotatable relation.
